US00D715347S

(12) **United States Design Patent**
Troxel

(10) **Patent No.:** **US D715,347 S**
(45) **Date of Patent:** **** Oct. 14, 2014**

(54) **DATA RECORDING DEVICE**

(71) Applicant: **Digital Ally, Inc.**, Lenexa, KS (US)

(72) Inventor: **Jason R. Troxel**, Lee's Summit, MO (US)

(73) Assignee: **Digital Ally, Inc.**, Lenexa, KS (US)

(**) Term: **14 Years**

(21) Appl. No.: **29/467,962**

(22) Filed: **Sep. 25, 2013**

(51) **LOC (10) Cl.** **16-01**

(52) **U.S. Cl.**

USPC **D16/202**

(58) **Field of Classification Search**

(57) **CLAIM**

The ornamental design for a data recording device, as shown and described.

DESCRIPTION

FIG. 1 is a front and right perspective view of a data recording device showing my new design;

FIG. 2 is a rear and left perspective view of the data recording device of FIG. 1;

FIG. 3 is a front elevation view of the data recording device of FIG. 1;

FIG. 4 is a rear elevation view of the data recording device of FIG. 1;

FIG. 5 is a top plan view of the data recording device of FIG. 1;

FIG. 6 is a bottom plan view of the data recording device of FIG. 1; and

FIG. 7 is a left side elevation view of the data recording device of FIG. 1; and,

FIG. 8 is a right side elevation view of the data recording device of FIG. 1.

The broken lines depict portions of the data recording device in which the design is embodied and form no part of the claimed design.

1 Claim, 4 Drawing Sheets
